UNITED STATES PATENT OFFICE.

WARREN H. TAYLOR, OF STAMFORD, CONNECTICUT, ASSIGNOR TO THE YALE & TOWNE MANUFACTURING COMPANY, OF STAMFORD, CONNECTICUT.

CYLINDER-LOCK.

No. 874,808.

Specification of Letters Patent.

Patented Dec. 24, 1907.

Application filed October 1, 1907. Serial No. 395,434.

To all whom it may concern:

Be it known that I, WARREN H. TAYLOR, of Stamford, in the county of Fairfield and State of Connecticut, have invented certain new and useful Improvements in Cylinder-Locks; and I do hereby declare the following to be a full, clear, and exact description of the invention, such as will enable others skilled in the art to which it appertains to make and use the same.

My invention relates to an improvement in cylinder locks of the pin tumbler type, the object being to provide means for preventing the destruction of the pins and drivers by a boring tool entered through the face of the lock.

With this end in view my invention consists in the parts and combinations of parts as will be more fully explained and pointed out in the claims.

In the accompanying drawing, Figure 1 is a view in front elevation of a pin tumbler lock showing my improvement in dotted lines, and Fig. 2 is a view in vertical longitudinal section of same.

It is well known that the pins of a pin tumbler lock may be destroyed by drilling a hole through the top of the plug and adjacent part of the cylinder, in the plane of the pins, thus leaving the plug free to be turned in a direction to unlock the lock.

To prevent the possibility of access to the pins by means of a boring tool, I provide the cylinder 1 of the lock with an armor consisting of a hardened steel pin or plate 2 extending preferably from the top of the cylinder at the top of the plug 4, and intermediate the pin tumblers and escutcheon. I also provide the plug 4 with a similar armor 5 extending throughout the diameter of the plug, in the plane of the key way, the armor being slotted for the passage of the key. The armors 2 and 5 which are preferably in the form of pins or plates, are secured in place in

the cylinder and plug respectively, in line 45 with the tumbler pins and drivers 6 and 7, and absolutely prevent the possibility of destruction of all the tumbler pins by boring through the front. This armor need only be wide enough to prevent a tool entered from 50 the front plate, from engaging and destroying all of the tumbler pins, hence a boring tool entered at the side of the hardened steel pins or plate could not be manipulated to reach all the pins.

It is evident that many slight changes might be resorted to in the relative arrangement of parts shown and described without departing from the spirit and scope of my invention hence I would have it understood 60 that I do not wish to confine myself to the exact construction shown and described, but,

Having fully described my invention what I claim as new and desire to secure by Letters-Patent, is:—

1. As a new article of manufacture, a pin tumbler lock having a protecting armor located within the cylinder in advance of the pins.

2. As a new article of manufacture, a pin 70 tumbler lock having a protecting armor located within the cylinder and plug in advance of the pin.

3. As a new article of manufacture, a pin tumbler lock having a protecting armor located within the cylinder, and a protecting armor located within the plug, the armor in the plug being slotted for the passage of the key, the armors in the cylinder and plug being located in advance of the pin tumblers. 75

In testimony whereof, I have signed this specification in the presence of two subscribing witnesses.

WARREN H. TAYLOR.
